[57] CLAIM

The ornamental design for an outdoor lighting fixture, as shown and described.

DESCRIPTION

FIG. 1 is a top, side perspective view of an outdoor lighting fixture;

FIG. 2 is a top plan view thereof;

FIG. 3 is a front fragmentary elevational view thereof;

FIG. 4 is a fragmentary side elevational view thereof;

FIG. 5 is a fragmentary rear elevational view thereof; and

FIG. 6 is a bottom plan view thereof.

The standard is fragmentarily shown in FIGS. 3, 4 and 5 for convenience of illustration. The base in FIG. 1 and the lamp bulb in FIG. 6 are shown in broken lines for illustrative purposes only.

FIG. 1

FIG. 2
